COMBINATION BATHTUB AND TOILET FIXTURE

Lester D. Ehmke, Sebastopol, Calif.

Application May 11, 1953, Serial No. 24,947

Term of patent 14 years

(Cl. D4—4)

Fig. 1.

Fig. 2.

Fig. 4.

Fig. 3.

Fig. 1 is a top plan view of the combination bathtub and toilet fixture with the toilet fixture cover closed, showing my new design;

Fig. 2 is a front side elevation of the combination bathtub and toilet fixture, the far side and left-hand end being open;

Fig. 3 is a right-hand end elevation showing the toilet fixture; and

Fig. 4 is a right-hand end elevation of the toilet fixture with the cover raised.

I claim:

The ornamental design for a combination bathtub and toilet fixture, as shown.
